UNITED STATES PATENT OFFICE.

E. WOLCOTT DANIELS, OF SPRINGFIELD, MASSACHUSETTS.

MACHINE FOR PICKING MILLSTONES.

Specification of Letters Patent No. 26,897, dated January 24, 1860.

To all whom it may concern:

Be it known that I, E. WOLCOTT DANIELS, of Springfield, in the county of Hampden and State of Massachusetts, have invented a 5 new and useful Improvement in Machines for Picking Millstones; and I do hereby declare that the following is a full, clear, and exact description of the same, reference being had to the annexed drawings, making a 10 part of this specification, in which—

Figure 1, is a side view of my invention applied to a machine for picking mill stones. Fig. 2, is a plan or top view of ditto.

Similar letters of reference indicate corresponding parts in the two figures.

This invention relates to an improvement in those machines for picking mill stones which have the pick shaft fitted in a sliding frame attached at one end only to the bed-piece or stock of the machine as may be seen for instance in the machine of S. W. and R. M. Draper patented May 25th, 1852, May 20 18th, 1856, and April 19, 1859.

The object of the within described invention is to obtain a more delicate and perfect adjustment of the pick so that the stones may be "cracked" or picked between the large or master furrows in a more perfect manner than hitherto.

30 To enable others skilled in the art to fully understand and construct my invention I will proceed to describe it.

A, represents a bed-piece on which a horizontal cam B, is placed, said cam, when the 35 machine is to be used, being placed on the spindle of the stone or on a shaft arranged for the purpose and concentric with the stone. The latter arrangement would be necessary in picking an upper stone or runner. In picking the bed or stationary stone, the cam is adjusted on the spindle. The bed-piece A, has curved bars a', attached to its under side, which bars rest on the face of the stone to be picked, and to this bed-piece a lever frame C, is placed and allowed to work freely on its fulcra a, a. The lever frame C, is formed simply of a bar b, attached to arms c, c, one at each end as shown clearly in Fig. 2. This lever frame is actuated by the cam B, and a spiral spring E, the latter being on a rod F, pivoted to an upright e, hereinafter described, and which rod is fitted within a forked arm G, attached to a pick shaft H, and which arm is 55 provided with a laterally projecting pin d,

that extends over the bar b, of the lever frame C. The cam B, gives the upward movement to the lever frame and the spring E, the downward movement or blow of the pick I, which is placed in a stock J, that is attached to an arm K, said arm being fitted on the shaft H, and allowed to slide thereon.

The pick shaft H, is fitted in a frame L, which is formed of two end pieces connected by a cross bar g. The bearings of pick shaft H, are in the end pieces, the shaft being allowed to work freely in its bearings. One of the end pieces is fitted on a guide h, at the side of the bed-piece A, and allowed to slide freely back and forth thereon.

On the bed-piece A, a rack M, is secured, parallel with the guide h. Into this rack a pinion L', gears, said pinion being on a rod i, which is fitted longitudinally in the frame L, and has a hand wheel k, on its outer end. 75 By turning the rod i, the frame L, is moved and the pick I, adjusted in planes at right angles to the bed-piece A.

The above described parts form essentially the machine of S. W. and R. M. Draper, previously alluded to. This machine as well as others similarly arranged performs well for cutting or dressing the large or master furrows α , as a very nice or delicate adjustment of the pick for such purpose is not essential, but in "cracking" the stone, that is to say, in forming small furrows b , about 18 or 20 to the inch, between the large furrows α , a very nice adjustment is required in order to have the small furrows parallel 90 so that they will not intersect or run into each other. A result of that kind would materially detract from the efficiency of the stones. In the machine of Drapers and others when the frame L, is moved by a rack and pinion L' as shown, the pick shaft H, cannot be adjusted perfectly at right angles to the bed-piece for the action of the pinion i, on the rack M, has a tendency to throw the adjoining end of the frame L, forward 95 in advance of the opposite outer end. And also, for want of means to hold the upright (e) firmly to the guide (h) there is a tendency to produce a slight vibration or movement back and forth, laterally, of the frame L and pick shaft H; which vibration is fatal to accuracy in the cutting of the small furrows.

My invention consists in the arrangement in combination with the movable frame 110

aforesaid of an additional adjustable frame, in which the picker is hung in the manner hereinafter described.

On the guide *h*, a bar *N*, is placed and allowed to slide freely. To this bar *N*, a bar *O*, is attached at right angles, and to the outer end of bar *O*, and to the bar *g*, of frame *L*, a bar *P*, is attached at right angles and consequently parallel with *N*, see Fig. 2.

- 10 In the bar *O*, two screw rods *Q*, *Q*, are placed, which work in nuts *R*, *R*, one of which is attached to the upright *e*, and the other to the upright *f*, of frame *L*. It will be observed that the uprights (*e*, *f*), slide 15 upon guides upon the upper parts of the end pieces of frame *L*. The front ends of the screw rods *Q*, *Q*, have each a bevel pinion *m*, on them and these pinions gear into corresponding pinions *g'*, *g'*, on a shaft *R'*, one 20 end of which has its bearing in the bar *N*, and the other end its bearing in a plate *h'*, attached to bar *P*. The upright *f*, of the frame *L*, is fitted on a guide *n*, on the bar *P*.

From the above description it will be seen 25 that in cutting the large or master furrows, the frame *L*, may be adjusted in the old way, viz., by the rack *M*, and pinion *i*.

In order to cut the smaller furrows, or to 30 adjust the picker so that it will accurately cut the small furrows, the operator turns the shaft *R'*, which, through the medium of pinions *g'*, *g'*, *m*, *m*, and screws *Q* causes the uprights (*e*, *f*), and with them the picker and shaft, to advance or recede, as may be 35 desired. As both of the end pieces or uprights (*e*, *f*) slide upon ways, and as equal power is applied to them simultaneously through the screws *Q* it is manifest that the picker and its shaft will move on an exactly 40 straight line, and the cuttings will all be parallel; and their distance apart may be regulated to the utmost fineness and nicety.

In the other machines before noticed, the outer end piece of the frame which supports 45 the picker shaft, rests upon the stone, while the inner end piece runs upon a guide; the picker frame is thus rendered difficult of movement by reason of the friction of the outer end piece upon the stone; and there is,

moreover, a tendency, from the same cause, 50 to throw the inner end piece forward or in advance of the outer end piece, thus displacing the picker shaft, and rendering its useful employment to cut the fine furrows impossible. If these finer furrows are not accurately cut the wheat will not be properly ground, and large proportions of refuse called "middlings" will be made, to the loss of better flour. My improvement enables the miller to dress his stones, including the 60 fine furrows, with an accuracy hitherto unknown; and the resulting advantages are a greater uniformity in the quality of the flour, and an increase in the quantity of good flour from a given amount of grain. 65

As an additional security to nicety and accuracy of work I have devised a locking device (*l*) which is placed on the bar *N*, for the purpose of locking said bar and with it the frame *L* to the bed piece *A* and thus preventing lateral vibrations thereof during the operation of the picker. The lock I have shown consists of a screw passing through the bar *N* and bearing against the bed piece *A*. When the frame *L* is thus locked it cannot, of course, be moved by the pinion (*i*); but the picker shaft and picker may be moved, by turning the shaft *R'*, as before described. Any suitable locking device may be employed, nor is any particular position 70 essential, so long is it will firmly hold the frame *L*, and prevent its vibration.

I claim none of the parts shown in Draper's patent aforesaid, but

Having thus described my improvement, I 85 claim as new, and desire to secure by Letters Patent:

The combination with the frame *L* of the additional frame consisting of the bars *N*, *O*, *P*, and the shaft *R'*, locking device, *l*, pinions *g'*, *g'*, *m*, *m*, and screws *Q*, *Q* arranged and operating substantially as described for the purpose specified. 90

E. W. DANIELS.
